FILLING MACHINE WITH ROTARY VALVE

Leonard McGihon, San Leandro, Calif., assignor
to King Sales & Engineering Company, San
Francisco, Calif.

Application November 19, 1946, Serial No. 710,814

5 Claims. (Cl. 226—97)

1

The present invention relates to canning machinery and is concerned more particularly with a filling machine for completing the fill of a can or container with a syrup or sauce.

It is a general object of the invention to provide an improved filling machine of the character commonly employed in canneries.

Another object of the invention is to provide a machine of the above character which operates to insure proper positioning of the contents within the container and to thereafter complete the fill of the container with a sauce or syrup.

Another object of the invention is to provide machinery of the above character which is of a flexible nature and adaptable for use in various positions in a canning line.

A further object of the invention is to provide a machine of the above character employing a presser for insuring proper positioning of a product within a container and for cutting off any portions of the product which project beyond the side wall of the container and for thereafter effecting the stripping of the container from the pressing head in an advantageous manner.

A further object of the invention is to provide a filling machine in which unnecessary operations of the filling valve are eliminated.

Other objects and advantages of the invention will be apparent from the following description of a preferred embodiment thereof as illustrated in the accompanying drawings, in which:

Figure 1 is a plan view of a machine embodying the invention.

Figure 2 is a side elevational view of the machine shown in Figure 1.

Figure 3 is a vertical sectional view of the pressing turret of the machine taken in the plane indicated by the line 3—3 in Figure 1.

Figure 4 is a fragmentary sectional view taken as indicated by the line 4—4 in Figure 3.

Figure 5 is a vertical sectional view of the filling turret and associated mechanism taken as indicated by the line 5—5 in Figure 1.

Figure 6 is a fragmentary sectional plan view of a filling valve taken as indicated by the line 6—6 in Figure 5.

Figure 7 is a bottom plan view of one of the filling heads of each filling valve.

In connection with the canning of fish, such as sardines, it is customary to pack the fish in an oval-type can or container with the fish alternately arranged as to the positions of the heads and tails. The fish usually project above the top of the can and quite often one or more of

2

the tails of the fish will protrude slightly over the edge of the can. As a result, most cans require a pressing or tucking of the fish into the can as a preliminary to the saucing or syruping of the can.

The instant machine is of the type to receive cans filled with fish and to thereafter pass the cans in an automatic fashion through a pressing or tucking turret to insure proper disposition and 10 positioning of the fish within the cans and then to transfer the cans to the saucing or syruping turret in which the cans are vacuum filled in the appropriate amount with a sauce and are subsequently discharged from the machine for feeding to a conventional form of can closing machine.

Referring to the drawings, the machine includes a frame or body portion 10 (Figures 1 and 2) which is symmetrical end for end and includes 20 appropriate mounting stations for a pressing or "tuck-in" turret 11 and a filling or syruping turret 12, as described in greater detail hereinafter. The frame 10 also provides an adjustable pivotal mounting for a can feed mechanism 13 and for 25 a drive unit 14.

It will be understood that the cans are received by the feed unit 13 which transfers them to the pressing turret 11 where the proper positioning of the contents is insured. From the 30 pressing turret the cans are transferred to the syruping turret 12 where the desired amount of sauce or syrup fill is performed.

Can feed mechanism

The can feed mechanism 13 (Figures 1 and 2) includes a support bracket 21 which is supported adjustably on the frame by means of a bracket extension 21a pivoted about the shaft 22 of the feed star wheel 23 referred to hereinafter. The shaft 22 is supported and journalled both in the frame 10 and the frame bracket 10a. The bracket 21 of the can feed mechanism is capable of adjustment about the axis of the shaft 22 between the full and dotted line positions thereof shown in Figure 1 and is held in position by means including a series of equally spaced bolts 25. By selective aligning of the holes for the bolts 25 the angular position of the bracket 21 can be adjusted, and in this way, the machine is adaptable for can feed from various directions.

The bracket 21 supports a double chain conveyor 24 trained about respective driving and idler drums 27 and traveling in respective grooves 28 of the bracket 21. Parallel to the chain conveyor 24 is a timing worm 29 of tapered con-

struction which is journaled in respective similar brackets 30 on the table 21 for engaging a can travelling on the chains 24, and for retarding its travel to the desired speed at which the feed to the machine is to be performed. The worm 29 is driven by means including spiral gearing 31, a spur gear 32, an idler gear 33, and a gear 34 on the shaft 22 which serves to drive the star wheel 23 in timed relation with respect to the timing worm 29. The gear 34 is driven in a manner later described from the drive mechanism 14. A guide rail 36 extends from the right-hand bracket 30, as viewed in Figure 1, over the turret 11. The rotation of the timing worm 29 is such that cans are fed successively to each of the three arms of the star wheel 23 for propelling thereby along the rail 36 into the pressing turret of the machine.

Pressing turret

The pressing turret includes an endless series of vertically aligned can supports and pressing heads for receiving cans successively from the feed mechanism and for aligning and holding each can to for entry of the pressing head into the can to insure proper packing of the product therein. Each pressing head also includes a stripper plate or disk which is effective to maintain the can on its support at the time the pressing head is stripped or withdrawn from the can. Each pressing head also has associated therewith a wiper for cleaning off the top edge of a can. In the present embodiment, the pressing turret as well as the other parts of the machine are adapted for use with an oval type can in which fish are packed.

As shown in Figures 1, 2 and 3, the frame 10 is provided with an opening to receive an upper bearing and support collar 41 for a drive sleeve 42 and a stationary support shaft 43 within the sleeve 42. A lower bearing and supporting collar 41' for the sleeve 42 is carried by a frame bracket 10a spaced below and supported from the frame 10. The shaft 43 is supported at its lower end in a tubular support bracket 40 depending from the frame bracket 10a. The pressing turret 11 includes a rotary table 44 which has its hub 44a keyed to the sleeve 42 at 46, and the lower end of the hub 44a is received within a retaining guide collar 47. The table 44 forms a can support in cooperation with a turret plate 48 bolted thereon and having a series of evenly spaced can-receiving recesses 48a in the periphery thereof.

Opposed to each of the can receiving recesses 48a (Figures 1 and 3) are a pair of can engaging and aligning fingers 49 carried by a transverse shaft 51 in a bearing block 52 secured below the table 44 at each can support. Each shaft 51 carries a gear 53 meshing with a rack 54 for controlling oscillation of the aligning fingers 49. The rack 54 in turn is controlled by the engagement of a roller 56 thereon within a cam track 57 secured on the main support table 10. As will be described later, each pair of aligning fingers 49 cooperates with the associated can receiving recess 48a to align the can with the associated pressing head.

Aligned with each of the can supports provided on the can table 44, there is mounted a can engaging head indicated generally at 61 (Figures 1, 2 and 3) which includes a support sleeve 62 guided for vertical movement in a boss 63 of a spider 64 keyed at 66 on the sleeve 42. Each of the sleeves 62 adjacent its upper end carries a roller 67 engaging within a cam track 68 supported by a casting 84 on the center post 43. The cam track 68 serves to control the vertical posi-

tioning of the respective pressing heads 61. At its lower end, each head 61 includes an oval plate 71 conforming to the contour of the can being filled and having pressing lips 72 adjacent each end thereof for entry within the can in close contact with the wall thereof. The pressing head 61 has a hub 71a secured on the sleeve 62 and providing a journal support for a four-armed wiper 73 for engaging the top edge of the can. The rotative position of the wiper 73 is controlled by four spaced aligning recesses 74a therein (Figure 4) connected by grooves and cooperating with a spring-pressed ball 76 seated within a collar 77 secured on the sleeve 62.

The pressing head 61 (Figure 3) also includes a central stripper disk or plate 78 which is guided within the sleeve 62 and projects upwardly therethrough at 78a for independent control of the vertical movement thereof. As shown, the stripper 78 floats with respect to the pressing head 61 and is raised vertically with respect thereto when the head is lowered into engagement with a can as shown in Figure 3.

For controlling the wiping movement of the four-armed wiper 73, there is provided a roller 81 (Figures 1 and 2) carried by an arm 82 and disposed to engage one of the wiper arms 73a of each station of the turret and turn each wiper through an angle of 90° so that the top edge of a can is cleaned off. Also a wiper arm 73a of each head is positioned for cooperation with the roller 81 on the next succeeding rotation of the turret, and is held in position by the ball latch 76.

For control of the stripper disk 78 of each head, a plate 83 (Figure 1) is secured on the casting 84 in which the cam track 68 is formed in a position to engage the upper end 78a of the stripper. During the time that the cam track 68 lifts the presser head 61 to disengage the presser plate 71 from within the can, the stripper disk 78 is held in engagement with the contents of the can by the plate 83 and thereby holds the can against lifting with the presser plate 71.

The drive for the table 44 is transmitted thereto through the sleeve 42 from a gear 79 keyed thereon and driven in a manner later described.

Transfer means

The means for transferring cans from the pressing turret 11 to the filling turret 12 includes a star wheel 86 (Figures 1 and 2) carried by a shaft 87 which is suitably journaled in the frame 10 and the frame bracket 10a. The shaft 87 carries a gear 88 meshing with the gear 19 and with a gear 89 of the filling turret. Cooperating with the transfer star wheel 86 is a transfer support plate 91 which extends between the turrets 11 and 12, and a rail or fence 92 which extends inwardly over the table 44 of the pressing turret to guide a can out of the turret socket while it is propelled by the turret. Thereafter one of the arms of the star wheel 86 contacts the trailing end of the can to complete its removal from the presser turret 11 and transfer it to a similar socket 65 of the filling turret 12.

Filling turret

The filling turret operates to receive cans in which the fish or other contents are in proper position therein by virtue of the pressing operation previously performed, and to vacuum fill these cans with an appropriate amount of sauce to a desired head space within the can. The turret includes a series of filling valves and operating can lift members which are progressed

past a filling station for opening of a valve having a can associated therewith, and then past a closing station which closes the valve after the filling operation is completed.

The filling turret 12 (Figures 1, 2 and 5) includes a support shaft 101 which is journaled in an upper bearing member 102 carried on the frame 10 and in a lower bearing member 103 also supported on the table by means including the frame bracket 10a. Between the bearing members 102 and 103 the gear 89 is keyed to the shaft 101. The shaft 101 has keyed thereto a filling table 106 having a plurality of bosses 107 around the periphery thereof containing bearing supports 108 for a series of can lift members 109. Each can lift member 109 includes an upper can support plate 109a and a lower roller 109b which cooperates with an annular cam track 111 on the frame 10. The filling table 106 also carries a can positioning spider 112 having a series of recesses 112a about the periphery for engagement by a can as shown, for example, in dotted lines at 113 in Figure 5.

The shaft 101 (Figures 1, 2 and 5) at its upper end has secured thereon a tank for containing the sauce to be filled and the tank includes a bottom wall 116 having a side wall 117 secured thereon. The bottom wall 116 provides a support for a series of similar filling valves, each filling valve including a center post 118 having a lower guide extension 118a seated in a cooperating recess in the bottom wall 116 of the tank. At its upper end each post 118 is secured to a ring 119 by means of clamping nuts 121. Disposed about the center post 118 is a valve member or sleeve 122 having a pair of opposite extensions 123 (Figures 5 and 6) in engagement with the bottom wall 116 of the tank and adapted to selectively open and close respective diametrically opposed openings 124 therein upon successive 90° rotations of the sleeve. A spring 125 urges the sleeve 122 downwardly to seat its extensions 123 against the bottom wall 116 of the tank.

For the purpose of controlling the rotated position of the valve sleeve 122, it is provided with a four-armed spider 126 at the upper end thereof. Each alternate arm of the spider 126 carries an upwardly projecting roller 128, while the other alternate pair of arms thereof carry downwardly projecting rollers 129. The rollers 128 comprise valve opening elements disposed in one plane, while the rollers 129 are valve closing elements disposed in another plane.

Each filling valve mechanism also includes a can engaging head in the form of a plate 131 (Figures 5 and 7) which carries a resilient can engaging seal member 132 in a shape conforming to the oval shape of the can and a head-space plate 133 within the outline of the seal member 132. The head plate 131 is provided with a pair of passages 134 aligned with the passages 124 in the tank wall and also with corresponding passages in the head-space plate 133, which open into a cross shaped groove 135 in the bottom surface of the head-space plate 133.

To provide for vacuum filling of the cans, the lower surface of the head plate 131 has a diagonal groove 136 therein which extends beyond the head-space plate 133 to open into the end spaces of a can, and also communicate with the central opening of the head plate. Also the guide extension 118a of each guide post 118 has a passage 141 opening into a radial passage 142 in the bottom tank wall 116. The passage 142 opens upwardly into a counter bored aperture 143

formed in a vacuum ring 144 secured on the tank wall 116. A cooperating stationary vacuum ring 146 is provided which is held against the ring 144 by a plurality of conventional presser members 147 (Figure 1), and this stationary ring 146 has a segmental annular groove 145 for cooperation successively with the apertures 143 of each of the filling valves as they rotate through the filling zone. As seen in Figure 1, the vacuum ring 146 has a connection 148 leading to a suitable source of vacuum and the extent of the vacuum recess 145, as seen in Figure 1, is such that an appropriate vacuum is applied to the can before the associated filling valve is opened.

In order to control the operation of the filling valves, a suitable form of no-can-no-fill device is provided which is responsive to the presence of a container to cause operation of the filling valve from closed to open condition. As seen in Figures 1, 2 and 5, at the filling or opening station of the filling turret there is provided an arm 151 pivoted at 152 in a suitable mounting bracket 153 supported on the frame 10 and spring-urged upwardly by a compression spring 154 surrounding a pull rod 156 guided in the bracket. The pull rod 156 extends downwardly and is connected to an arm 157 secured on a shaft 158 journaled in the cam track 111 and carrying an arm 159 at its other end for engagement by a roller 161 supported coaxially with the roller 109b. Adjacent the roller 161 is a smaller roller 162 which is provided for depressing the can lift members by means of a suitable cam (not shown).

From the above description it will be seen that the arm 159 is spring urged upwardly and extends along and adjacent to the raised portion of the cam track 111 for lifting the can lift members. Normally the arm 159 is slightly above the cam track 111. The strength of the spring 154 is so selected that it can raise the can lift member 109 off of the track 111 if no can is on the member, and the valve opening arm 151 will remain in its normal dotted line position shown in Figure 5. In this position a roller 128 will pass beneath the arm 151 and the valve associated with the empty can lift will not be opened. However, when a can is interposed between the lift member 109 and the head 131, a positive block is provided against further lifting of the can lift member 109 by the arm 159 and the spring 154 so that the arm 159 is depressed by the can lift member. Correspondingly, the arm 151 is depressed to the full line position shown in Figure 5. As a result, a roller 128 will strike this arm and the filling valve sleeve 122 will be rotated 90° so that one of the valve closing rollers 129 will be in the outward active position ready for cooperation with a valve closing member.

The valve closing station comprises an arm 166 mounted by a bracket 167 on the frame 10, and disposed in the plane of the valve closing rollers 129. It will be recalled that when a valve is opened, a closing roller 129 is moved to active position. Thus a filling valve which has been opened to fill a can will be closed by engagement of the active roller 129 with the arm 166 and this 90° movement of the valve sleeve 122 will again bring a roller 128 to active position for cooperation with the valve opening station on the next succeeding rotation of the filling turret.

To provide for opening of the filled cans to atmosphere and for resultant gravity comple-

tion of the filling operation, if desired, the "vacuum" ring 146 has a segmental arcuate groove 168 which is open to the atmosphere through the associated aperture in an associated presser member 147.

Cans are discharged from the filling turret by means including a suitable discharge support plate 171, a rail or fence 172 and a star wheel 173.

Drive unit

The star wheel 173 (Figures 1 and 2) is carried by a shaft 174 which also carries a drive gear 175 for the filling turret gear 89 and also provides a mounting or pivotal support for a drive unit including a bracket 177 which carries a shaft 178 and a sprocket 179 for receiving a drive. The bracket 177 is secured to the frame bracket 10a by a series of equally spaced bolts 181 providing for connection of the drive unit in a selected angular location. The shaft 178 is connected through a bevel pinion 182 and a bevel gear 183 to the shaft 174 to transmit the drive thereto.

As seen in Figure 1, the drive mechanism can be adjusted at any selected position between the full and dotted line positions thereof shown. Also, by installing a shaft such as 174 for supporting the feed star wheel 23, the drive unit 14 can be mounted below the feed unit 13.

In operation cans in which the product such as sardines has been placed are fed into the machine by the conveyor 24 and the feed star wheel 23 so that each can is moved into cooperative relation with a pressing head 61. Accurate alignment of a can with the cooperating head 61 is provided by the joint action of the aligning fingers 49 and the aligned recess 48a of the turret. During continued rotation of the turret the cam 68 operates to lower the pressing head so that the pressing plate 71 is moved within the can as shown in Figure 3 and wiping spider 73 is engaged with the upper edge of the can. The pressing plate 71 insures proper positioning of the fish within the can. In other words, any fish which is improperly positioned in the can is pressed down and will be positioned so as not to interfere with the can closing operation. Also, any fish which may project beyond the side wall of the can will either be tucked inside the can or will be cut off so that no portion of a fish can interfere with can closing. Subsequently, the roller 81 engages one of the arms 73a to rotate the wiping spider to 90° so that the top edge of the can is cleaned.

During continued rotation of the pressing turret the pressing head 61 is lifted by the cam track 68 at the time that the stripper plate 78 has its control shaft 78a disposed beneath the plate 83. In this way the can is prevented from following the withdrawal of the presser plate 71.

Subsequently, the can is removed from the pressing turret and fed to the filling turret by means including the fence 92 and the transfer star wheel 86 and is disposed on a can lift device 109 below one of the filling valves 126. Immediately before the filling valve and its associated container lift plate arrive at the zone occupied by the vacuum slot 145 (Figure 1), the can lift cam 111 becomes operative to engage the can with the filling head. Also the no-can/no-fill control lever 159 is depressed to move the arm 151 in the path of the upwardly projecting roller 128 on the filling head so that the filling valve is adjusted (rotated through 90°) to open the apertures 124 as seen at the left of Figure

6. In this view, the valve is part way adjusted between its closed and opened positions. The opening of a valve occurs after the associated can has passed beyond the zone of the vacuum groove 145.

At this time the sauce from the tank flows into the can under the pull of the vacuum therein. During the last portion of the filling operation, the space within the can is opened to atmosphere. This occurs when the passage 142 registers with the slot 168 so that a gravity completion of the fill can be obtained. Shortly, thereafter the downwardly extending valve closing roller 129 which is in active position engages the arm 166, and the filling valve is turned to its closed position. Thereafter the can is removed from the filling turret by the cooperation of the star wheel 173 and the fence 172 and is transferred to a closing machine of conventional character (not shown).

While I have shown certain preferred embodiments of the invention, it will be apparent that the invention is capable of further variation and modification and its scope should be limited only by the scope of the claims appended hereto.

I claim:

1. In a filling machine, a rotary filling valve having respective series of alternately arranged circumferentially spaced valve opening elements and valve closing elements, said respective series being staggered axially of the valve with all of the plurality valve opening elements lying in substantially the same plane and all of the plurality of valve closing elements lying in substantially another plane displaced axially of said first mentioned plane, means for moving the valve along a path, a valve opening station including a member for cooperation with said series of valve opening elements for selectively engaging the active element of the series to effect opening of the valve and a valve closing station along the path including means for cooperating with the series of valve closing elements to engage an active one of said elements to effect closing of the valve.

2. In a filling machine, a rotary filling valve having respective series of alternately arranged circumferentially spaced valve opening elements and valve closing elements, said respective series being staggered axially of the valve, means for moving the valve along a path, a valve opening station including a member for cooperation with said series of valve opening elements for selectively engaging the active element of the series to effect a partial rotation of the valve from closed to open position, said partial rotation being effective to move one of said valve closing elements to active position, and a valve closing station along the path including means for cooperating with the series of valve closing elements to engage an active one of said elements to effect closing of the valve by partial rotation thereof and also to bring one of said valve opening elements to active position.

3. In a filling machine having a rotary filling valve and means for moving the valve along a path, means for conveying a container along the path in cooperative relation with the valve, a valve opening station adjacent the path, a valve closing station adjacent the path, said valve including a bracket having an even number of radial fingers equally spaced circumferentially of the valve, one set of alternate fingers having mounted thereon and projecting in one axial direction respective valve control elements op-

erable by said opening station in effecting opening of the valve, and the other set of fingers having mounted thereon and projecting in the opposite axial direction elements operable by said closing station in effecting closing of the valve, one of said first-named elements being normally disposed for operation by said opening station to effect a partial rotation of said valve and bring one of the other set of fingers with the element thereon in active position for operation by said closing station.

4. In a filling machine having a filling valve and means for moving the valve along a path, means including a lift member for conveying a container along the path and for lifting it into cooperative relation with the valve, a valve opening station adjacent the path, a valve closing station adjacent the path, said valve including an element operable by said opening station to effect opening of the valve and a second element operable by said closing station to effect closing of the valve, said first element being disposed normally in effective position, a no-can-no-fill device associated with said opening station controlled by the lift member for causing operation of said first element only in response to the presence of a container in cooperative relation with the lift member and the filling valve, said second element being normally disposed in ineffective position and being movable with said first element upon operation thereof by said opening station to effective position.

5. In a filling machine having a rotary filling valve and means for moving the valve along a path, means including a lift means for conveying a container along the path and for lifting it into cooperative relation with the valve, a valve opening station adjacent the path, a valve

5
10

closing station adjacent the path, said valve including an element operable by said opening station to rotate the valve from a closed position thereof to an open position thereof, a second element operable by said closing station to rotate the valve from an open position to a closed position, said first element being disposed normally in effective position, and a no-can-no-fill device associated with said opening station controlled by the lift member for causing operation of said first element only in response to the presence of a container in cooperative relation with the lift member and the filling valve, said second element being normally disposed in ineffective position and being movable with said first element upon operation thereof by said opening station to effective position.
